UNITED STATES PATENT OFFICE

ROBERT P. HUTCHINSON, OF BETHLEHEM, PENNSYLVANIA

BUILDING LIGHTING

Application filed August 21, 1928. Serial No. 301,104.

This invention relates to buildings and more particularly to an improved form of mechanism for providing sunlight in those portions of a building normally shut off from 5 the direct rays of the sun.

An object of this invention is to provide a mechanism of this type, constructed and arranged so as to reflect light from natural sources into spaces which the light rays 10 would not ordinarily reach, such as the interiors of buildings or rooms, especially through windows on the north side of buildings or windows otherwise located at such times as they are not receiving direct sun- 15 light.

A further object is to provide a mechanism of the type set forth, constructed and arranged so as to reflect light into a building during daylight hours irrespective of the position or location of the sun with respect thereto.

These and other objects which will be apparent to those skilled in this particular art are accomplished by means of the invention 25 illustrated in the accompanying drawings, in which Figure 1 is a partial elevational view of the north side of a building provided with a mechanism constructed in accordance with one embodiment of this invention and Fig. 2 30 is a transverse sectional view therethrough, taken on the lines 2—2 of Fig. 1.

The particular embodiment of this invention which has been chosen for the purpose of illustration is shown in connection with a building 5, having windows or other openings 6 which may be so located, for example, on the north side thereof that the direct rays of the sun do not reach the associated rooms.

The present invention contemplates the 40 provision of means located on or adjacent to the roof of the building and formed so as to reflect light, such as the direct light from the sun, downwardly along the wall of the building past the windows, and this irrespective 45 of the position of the sun between the hours of sunrise and sunset. Reflecting surfaces are located in cooperative relation to each of the windows and in the path of a portion of the light rays reflected downwardly past the windows so as to divert these rays and direct

them inwardly through the windows to the interior of the room or building.

As illustrated, the reflecting mechanism which is located adjacent the roof of the building or in any other desired place where 55 it will receive the rays of the sun, includes relatively large, curved mirrors or reflecting surfaces 7 mounted upon supporting pins 8 formed on cross bars 9 which are mounted between supporting brackets 10, secured to 60 and extending outwardly from the building. Each reflecting surface 7 is so positioned that the rays of the sun are reflected by it downwardly past the various windows located therebelow, and the curve of the reflecting 65 surface is such that the sunlight is reflected downwardly irrespective of the position of the sun shining on the surface. Additional reflecting surfaces 11 are so associated with each of the windows 6 that a portion of the 70 rays reflected from the reflecting surface 7 at the top of the building are deflected and directed into the interior of the building through the associated window.

It will, of course, be readily understood 75 that the greater the number of reflecting surfaces 7 located adjacent the top of the building, the greater intensity of light will be reflected downwardly along the wall of the building. In the drawings, I have illustrated 80 two of the spheroidal reflectors, but, of course, any desired number may be employed for the purpose of reflecting a still greater intensity or amount of light into the secondary reflectors 11. A simple means for directing a 85 more intense light downwardly consists of a series of globular reflectors 12, mounted upon a supporting rod 13 secured to the supporting brackets 10, as illustrated. The result of this arrangement is the reflecting of a large 90 amount of sunlight downwardly along the associated wall of the building, and the deflection of this sunlight into the interior of the building. For example, assume light to come along a path generally indicated by a 95 line 13'. Rays of light striking the globes 12 will be reflected downwardly as indicated generally by the lines 14 and 15. The light following the pathway 14 strikes a mirror 11 in the upper portion of the building and is 100

reflected through the associated window to the interior thereof. The light following the path 15 passes the first mirror and strikes the next mirror where it is reflected into the associated room. The same is true of light 5 striking the globular reflecting surface 7. As a result, each secondary reflecting surface or mirror 11 receives light from each of the reflecting surfaces 7 and 12 during the entire 10 day, and sunlight is delivered to the interior of the building irrespective of the position of the sun.

Although I have described a specific embodiment of this invention, it will be apparent that various changes, additions, omissions and substitutions can be made therein without departing from the spirit of this invention or the scope of the appended claims.

What I claim as new and desire to secure 20 by Letters Patent is:

1. The combination of a building provided with windows or the like, of light reflecting mechanism including a convex reflecting surface arranged in a plane substantially 25 parallel to the wall of the building for directing a light downwardly along said wall and means for directing light through said windows to the interior of said building.

2. The combination with a building provided with windows and the like, of a plurality of reflectors having convex reflecting surfaces arranged in a plane substantially parallel to the wall of said building located so as to receive sunlight during the entire 35 day and to reflect such light downwardly along the wall of said building and means for directing said reflected light through said windows to the interior of said building.

3. The combination with a building provided with windows and the like, of a plurality of reflectors having convex reflecting surfaces located adjacent the top of said building, said reflectors being disposed in a plane substantially parallel to the wall of 45 said building so as to reflect sunlight downwardly along said wall during the entire day and a reflector associated with each of said windows for directing a portion of said reflected light to the interior of said building.

4. In a system of illumination for a building having windows therein, a stationary disc shaped reflector having a convex reflecting surface mounted above said windows and outwardly from the building, said convex 55 reflecting surface being disposed in a plane substantially parallel to the wall of the building so as to reflect rays of light downwardly along said windows, and means for deflecting said reflected rays of light through said windows.

5. In a system of illumination for a building having windows therein, a plurality of convex reflectors stationarily mounted above said windows and outwardly from the building and having the convex surface arranged

in a plane substantially parallel to the wall of the building so as to reflect rays of sunlight downwardly past said windows and means for deflecting said reflected rays of light through the windows.

In testimony whereof, I have hereunto subscribed my name this 17th day of August, 1928.

ROBERT P. HUTCHINSON.
